UNITED STATES PATENT OFFICE.

JOHN A. MILLER, OF ST. CHARLES, MISSOURI.

REDUCING-SOCKET RATCHET NUT-WRENCH.

SPECIFICATION forming part of Letters Patent No. 239,972, dated April 12, 1881.

Application filed January 25, 1881. (No model.)

To all whom it may concern:

Be it known that I, JOHN A. MILLER, of St. Charles, Missouri, have made a new and useful Improvement in Nut-Wrenches, of which 5 the following is a full, clear, and exact description, reference being had to the annexed drawings, making part of this specification in which—

Figure 1 is a side elevation of the improved 10 wrench; Fig. 2, an edge elevation; Fig. 3, an elevation of the side opposite to that shown in Fig. 1, the plate that incloses the pawl being removed; Fig. 4, a section taken on the line $x\ x$, Fig. 3, through the wrench proper; Fig. 5, 15 a section taken on the line $x'\ x'$, Fig. 3, through the wrench proper; Fig. 6, a section taken on the line $y\ y$, Fig. 3; Fig. 7, a detail, being a side elevation of that portion of the tool containing the pawl, the plate that incloses the 20 latter being shown in place; and Fig. 8, an edge elevation of the pawl-inclosing plate.

The same letters denote the same parts.

The present invention is an improvement in 25 that class of nut-wrenches which are operated by a ratchet and pawl, enabling the wrench to be turned continuously without removal from the nut to which it is applied by a backward and forward movement of the wrench-holder.

The improvement relates partly to the mode 30 of holding the pawl in the wrench-holder, partly to the means used in detaching the pawl from the ratchet, and partly to the construction of the holder-handle.

Referring to the drawings, A represents the 35 improved wrench, having the wrench proper, B, provided with the ratchet C, and the wrench-holder D, provided with the pawl E and handle F. The wrench B turns in the holder D in the usual manner, and is held in place there- 40 in as follows: The ratchet C is larger in di- ameter than the body b of the wrench, and when the wrench is in place one side, e , of the ratchet comes against the side of the holder, operating to hold the wrench in the holder in 45 one direction, and in the opposite direction it is held by means of a lip, e , with which the pawl E is furnished, and which lip, when the pawl is in engagement with the ratchet, comes against the side e' of the ratchet.

50 The pawl E is held in the holder as shown in Fig. 3, the inner end, e' , of the pawl being rounded and bearing, when engaging with the

ratchet, against a seat, e^2 , of corresponding curvature in the handle. The pawl is also furnished with a projection, e^3 , by means of 55 which the pawl can be drawn away from the ratchet. The pawl is forced against the ratchet by means of a spring, G, which is preferably a coil-spring, as shown, and which encircles a projection, g , on the pawl, the inner end of the 60 spring being conveniently held in a socket, f , in the handle, as seen in Fig. 3. The socket f also receives the outer end of the projection g as the pawl is drawn backward from the ratchet. As the pawl is thus withdrawn by 65 means of the projection e^3 , its inner end, e' , has a tendency to slip out of the bearing e^2 . To prevent this the pawl is perforated at e^4 to admit a pin, h , which may be attached to the main portion of the holder, but which is pref- 70 erably attached to a plate, H, Figs. 7 and 8. After the pawl has been put in place, as seen in Fig. 3, the plate H, by means of suitable screws, h' , is attached to the holder inclosing the pawl, and the pin h , passing into the perforation e^4 , 75 serves to keep the pawl from slipping from its bearing. The pin e^4 , however, is not intended to support the pawl in operating the wrench, the strain then coming on the bearing e^2 .

The wrench, so far as turning the nut is concerned, is operated in the customary manner. 80

When it is desired to uphold the wrench upon a nut that is above the operator, (as in screwing nuts upon the under side of a railway-car,) a set-screw, I, Figs. 2, 3, 4, may be 85 advantageously used. By turning it inward the inner end of the screw is made to bind upon the nut and hold the wrench thereto. To remove the wrench from the holder the pawl is drawn backward sufficiently for the lip e to 90 clear the ratchet, whereupon the wrench can be lifted out of the cavity in the holder.

To avoid changing the wrench whenever a differently-sized nut is to be turned, the wrench may have reducing-sockets, such as shown at K, Figs. 1, 3, 4, 5. To hold the socket in place, a pin, k , having the head k' , is passed through the wrench and into or through the socket, as shown in Fig. 5. After the wrench is in the holder the pin k is prevented from slipping 100 backward out of place.

The holder-handle F is squared at f' , rounded at f^2 , and at f^3 is made narrow in the direction of the longitudinal axis of the cavity

in the wrench. To lengthen the handle F, a tube—such as a piece of gas-pipe—may, as indicated by the dotted lines in Fig. 3, be slipped onto the bearing f^2 , the end of the tube encountering the shoulders f^4 of the part f' . The wrench can thus be lengthened to any desirable extent, increasing its usefulness for railway-car work and similar operations where an increased leverage is needed. By making the handle narrow at f^3 , where the hand is applied, the wrench can be conveniently applied in turning nuts near to an extended flat surface.

I claim—

1. The combination of the holder D, having the rounded seat e^2 , the pawl E, having the rounded end e' , and the projection e^3 , the spring G, and the pin h, substantially as described.

2. The combination of the holder D, having the rounded seat e^2 , the plate H, and pin h, and the pawl E, having the projection e^3 , rounded end e' , and the perforation e^4 , substantially as described. 20

3. The combination of the wrench B, ratchet C, holder D, having the seat e^2 , the pawl E, having the rounded end e' , the projection e^3 , 25 and the perforation e^4 , and the spring G, and plate H, having the pin h, substantially as described.

JOHN A. MILLER.
